(57) **CLAIM**

The ornamental design for a mount for Christmas lights, as shown and described.

DESCRIPTION

FIG. 1 is a top perspective view of a mount for Christmas lights design showing my new design;

FIG. 2 is a bottom perspective view of the mount for Christmas lights design showing my new design;

FIG. 3 is a perspective view of the mount for Christmas lights design in a folding state showing my new design;

FIG. 4 is a front view of FIG. 1;

FIG. 5 is a rear view of thereof;

FIG. 6 is a left view of thereof;

FIG. 7 is a right view of thereof;

FIG. 8 is a top view of thereof;

FIG. 9 is a bottom view of thereof.

FIG. 10 is an exploded perspective view of the mount for Christmas lights design showing my new design;

FIG. 11 is an enlarged view of the selected portion “11” in FIG. 1; and,

FIG. 12 is an enlarged view of the selected portion “12” in FIG. 2.

Any shading and cross-hatching are not features of the design but are utilized to illustrate the surface contours of the mount for Christmas lights design in the drawings. The broken lines depict portions of the mount for Christmas lights design, and form no part of the claimed design. The dot-dash broken lines in the drawings represent the boundaries of the enlarged portions which form no part of the claimed design. The break lines in the drawings indicate that the appearance of any portion of the mount for Christmas lights between the break lines forms no part of the claimed design.
